UNITED STATES PATENT OFFICE.

GEORGE W. McEWEN AND WILLIS H. LAWRENCE, OF MILTON, PA.

FENCE-POST.

SPECIFICATION forming part of Letters Patent No. 359,167, dated March 8, 1887.

Application filed December 20, 1886. Serial No. 222,101. (No model.)

To all whom it may concern:

Be it known that we, GEORGE W. McEWEN and WILLIS H. LAWRENCE, citizens of the United States, residing at Milton, in the county 5 of Northumberland and State of Pennsylvania, have invented certain new and useful Improvements in Fence-Posts, of which the following is a specification, reference being had therein to the accompanying drawings.

10 This invention relates to certain improvements in fence-posts and settings for the same; and it has for its objects to provide a firm and secure seat for such posts and to protect the post throughout its entire length, so as to render it 15 practically indestructible, as more fully hereinafter specified. These objects we attain by the means illustrated in the accompanying drawings, in which—

Figure 1 represents an elevation of our improved post and setting complete, and Fig. 2 a vertical sectional view of the same.

The letter A indicates a cylinder constructed of terra-cotta or burned earthenware of suitable dimensions. The said cylinder may be made 25 plain, but is preferably constructed with a flange or annulus, B, at its lower edge, in order to hold more firmly in the ground when set in position.

C indicates the base of the fence-post, which 30 is cylindrical or otherwise shaped to conform to the interior of the cylinder A, and of such diameter or exterior configuration as to leave a space, D, between its outer surface and the inner surface of the cylinder A, to be filled with cement, as more fully hereinafter set forth.

The letter E indicates the fence-post proper, which is constructed mainly of wood, either integral with the base above mentioned or set 40 in a recess in the upper end thereof. The said post is surrounded by one or more incasing-cylinders of terra-cotta or earthenware, F, of such diameter as to leave an intervening annular space, F', to be filled with cement or other preservative material.

45 The base of the post is of such length as to leave, when set in position, a space above its upper end, which can be filled with a preservative cement, and the upper end of the post is recessed for the reception of a preservative cement, which is filled into the recess.

50 Any suitable cement may be employed for

filling in the spaces between the setting and the incasing-cylinders of the posts; but coal-tar which has been boiled or heated until the volatile portions have been driven off, and in such condition as to solidify and harden, so as to 55 form a stable and secure connection, is preferable.

In making the post, the base of the same is placed in the cylinder A and centered as truly 60 as possible. The cement in a molten condition is then poured around the base and allowed to accumulate over its upper end. The surrounding sections are then placed around the post, and the space between the post and the same 65 is filled with the cement, which is allowed to accumulate over the top of the post, as shown.

In order to secure the fence wires or rails, the post and its incasing-cylinders are pierced or provided with suitable apertures, in which 70 are inserted suitable bolts, G, which project at each side of the post and form fastenings, to which the wires or rails may be connected.

It is evident that other than fence-posts may be made without departing from the spirit of 75 our invention.

Having thus described our invention, what we claim, and desire to secure by Letters Patent, is—

1. The combination of the post E, provided 80 with a suitable base, a cylinder, A, set into the ground and surrounding the said base, a filling of preservative cement interposed between the base and its cylinder, a terra-cotta or earthenware casing surrounding the post 85 E, and a filling of preservative cement interposed between the said casing and post, substantially as described.

2. The combination, with the post and its base, of the cylinder A, surrounding the said 90 base, the interposed filling of cement between the cylinder A and the base, the sectional casing F, surrounding the post, and the filling of cement interposed between the post and the casing F, substantially as described. 95

In testimony whereof we affix our signatures in presence of two witnesses.

GEORGE W. McEWEN.
WILLIS H. LAWRENCE.

Witnesses:

JOS. ANGSTADT,
